UNITED STATES PATENT OFFICE.

FRIEDRICH AUS DER MARK, OF ESSEN-ALTENESSEN, GERMANY, ASSIGNOR TO FIRM OF
K. & TH. MÖLLER GESELLSCHAFT MIT BESCHRÄNKTER HAFTUNG, OF BRACKWEDE,
GERMANY.

AIR FILTER.

Application filed March 29, 1923. Serial No. 628,553.

To all whom it may concern:

Be it known that I, FRIEDRICH AUS DER MARK, a citizen of the German Republic, residing at Essen-Altenessen, Germany, have invented certain new and useful Improvements in Air Filters (for which I have filed patent application in Germany March 20, 1922), of which the following is a specification.

10 This invention has reference to air-filters, and in particular to that class of air filters, comprising a plurality of adjacently arranged flexible chain-like members, and in which the space containing the dust or contaminated air is separated from the pure air space by an endless chain or a plurality of linked individual members the several links of which constitute the filtering elements. My invention is intended to improve 15 the construction and operation of devices of this kind, and in view thereof the invention refers to a peculiar configuration of the several small laminar plates constituting the chain links, and which are suspended in 20 substantially parallel relation to the air current to be treated.

In accordance with my invention these small laminar plates are provided with projections crossing the direction of the current, and forming obstructions by means 25 of which repeated deviation of the path of the current and a whirling effect are produced, such projections constituting pockets or troughs for collecting a suitable wetting and dust retaining adhesive liquid, such as oils, glycerine or any other suitable liquids.

In case such link chain filters are so arranged as to rotate forming circulating filters immersing into a wetting liquid, the 30 pockets formed by the projections carry the wetting liquids upwards in the rising run of the chain, and cause them to flow down in the descending run.

35 The projections are preferably V-shaped so as to allow the wetting liquid to collect in the receding angle thereof. The height of the projections above the plane of the several plates preferably corresponds to the 40 distance of the adjacent plates, and in a preferred form of construction the arrangement is such that the distance between the adjacent plates is determined by the shape of the projections referred to.

45 In a preferred modification the adjacent

plates are provided with their V-shaped projections alternating through 180 degrees relatively to each other, so that the V-shaped projections of one plate are crossing the corresponding projections of the adjacent plate.

50 My invention will be described with reference to the accompanying drawing, showing by way of example a preferred embodiment of the invention in Figure 1 as a front view of a filter; Figure 2 is a side view; Figure 3 is an elevation of one of the small plate members with V-shaped projections; Figure 4 is an elevation of an adjacent plate member showing how the V-shaped projections of the two plates are arranged at 180 degrees with relation to each other. Figure 5 shows a chain link in side view.

55 In the drawing:—S is the dust air space, R is the pure air space which is separated from the space S by a revolving or circulating filter formed by an endless chain K. The air to be treated is assumed to flow in the direction of the arrows indicated in Figure 2. The chain is shown supported by 60 sprocket wheels r, r¹ and with its lower end immersing into a container c charged with the wetting liquid.

65 The filter illustrated in the drawing by way of example is shown as an endless rotating chain filter which upon its passage through the wetting liquid takes up some of the liquid which is carried up in the rising run of the chain and is caused to be 70 dropped in the descending run. It is to be 75 understood, however, that the invention is also applicable to non-rotating or stationary filters of the kind referred to, thus for instance, it may be embodied in a chain which is rinsed from above with the wetting liquid. 80 In combination with these known constructions of filters my improvement will now 85 be described.

90 In accordance with my invention each chain link is formed by small laminar plates a, b which are strung adjacently to each other by means of holes e, forming a series of laminae upon the link bolts d of the chain. The laminae a, b are of exactly 95 the same shape and provided with projections or ribs f crosswise arranged with relation to the direction of the current, and which in the construction shown by way 100 of example constitute a V. The projections 105 are preferably stamped out of the material 110

- of the plates, and form pockets or troughs for collecting and for scooping up the wetting liquid in the receding angles of the V. The portions pressed out of the plane of each plate provide complementary ribs and recesses at the opposite faces of the plate, which baffle portions are preferably symmetrical with respect to a plane normal to the plate at the longitudinal axis thereof.
- 10 The plates are mounted adjacently to each other on the link bolts d in such a manner that the V-shaped projections of one plate are crossing those of the adjacent plate; so that in the two adjacent plates the projections f are arranged at right angle to each other, as clearly appears from Figure 4. Inasmuch as the plates are parallelly related to the direction of the air current the V-shaped projections form obstructions 15 against which the air impinges and is repeatedly deviated from its course and whirled, while the V-shaped projections of the plates of the rising run of the chain are scooping up the wetting liquid and carry 20 it upwards, and cause it to flow off from the descending run. The baffle portions which extend along the plates in the general direction of, but at an angle to the air stream, may be conveniently defined as arranged at an angle to the entering and trailing edges of the plates, which edges are, respectively, those edges presented towards the incoming air stream and those at which the air stream leaves the plates. The 25 projections of each plate are in contact with the plane surfaces of the adjacent plate so that the distance between two plates corresponds to the projections.
- 30 The laminary plates with the position of the V-shaped projections corresponding to Figure 3, are indicated in Figure 5 at I, where II indicates the position of the V-shaped projections corresponding to Figure 4, so that it appears from Figure 5 how the 35 plates I and II are alternating with each other.
- 35 The invention is susceptible of various modifications and changes in its several parts and in the combination thereof, so as to better adapt the same to varying conditions, and without deviating from the spirit of the invention as pointed out in the 40 claims.
- 45 I claim:—
- 50 1. In an air filter comprising a plurality of plates presented edgewise to the air stream, baffles between adjacent pairs of plates defining paths along the plates, said paths including portions arranged at an angle to each other and to the entering edges of said plates.
- 55 2. An air filter comprising a plurality of plates presented edgewise to the air stream, each of said plates having portions offset 60 from the plane of the plate to provide complementary ribs and recesses extending along said plate at an angle to the entering and trailing edges thereof, said plates being arranged to present the ribbed face of one plate to the recessed face of the adjacent plate.
- 65 3. An air filter comprising a plurality of plates, each of said plates having a ribbed and a recessed face, said plates being presented edgewise to the air stream and with the ribbed face of each plate presented towards the recessed face of the adjacent plate, the ribs and recesses of the opposed faces of adjacent plates being arranged at an angle to each other.
- 70 4. In an air filter, a plurality of plates disposed in parallel relation and rib-shaped projections on the plates partly filling the interspaces, said projections being generally V-shaped in elevation and symmetrically disposed relatively to a plane transverse of the direction of the air current.
- 75 5. In an air filter of the endless chain type, a chain the links of which are composed of a plurality of plates in parallel relation and presented edgewise to the air stream and baffle projections on the plates of each link defining tortuous paths for the air currents, said baffle projections extending along said plates and at an angle to the entering and trailing edges thereof, some at least of the projections of each plate being of such height as to contact with the adjacent face of the adjoining plate.
- 80 6. In an air filter of the endless chain type, a chain the links of which are composed of a plurality of plates in parallel relation, baffle portions provided by ribs and recesses extending along each of said links at the opposite faces thereof to define tortuous paths for the air currents, the baffle portions of each link being arranged at an angle to the edges thereof, and the baffle portions at the opposed faces of adjacent links being positioned at an angle to each other.
- 85 7. In an air filter of the endless chain type, a chain the links of which are composed of plates in parallel relation and rib-shaped projections on the plates of each link partly filling the interspaces, said projections being generally V-shaped in elevation and symmetrically disposed relatively to a plane normal to the links at the longitudinal axis thereof.
- 90 8. In an air filter, a plurality of plates disposed in parallel relation and provided with grooves in one surface defining corresponding ridges on the opposite surface, said grooves and ridges being generally V-shaped in elevation and symmetrically disposed relatively to a plane transverse of the direction of the air currents.
- 95 9. An air filter, the dust-space of which is separated from the pure air space by an

- endless chain, each chain link being composed of laminary plates strung up in parallel relation to the flowing direction of the air to be treated and provided with projections crossing the air direction, the height of such projections corresponding to the distance of the laminary plates from each other. 5
10. An air filter, the dust space of which is separated from the pure air-space by an endless chain, each chain link being composed of laminary plates strung up in parallel relation to the flowing direction of the air to be treated and provided with projections crossing the air direction, the height 15 of such projections corresponding to the distance of the laminary plates from each other and forming pockets or troughs for receiving an adhesive liquid for retaining the dust. 10
20. 11. An air-filter, the dust-space of which is separated from the pure air space by an endless chain, each chain link being composed of laminary plates strung up in parallel relation to the flowing direction of the air to be treated and provided with projections crossing the air direction, the height 25 of such projections corresponding to the distance of the laminary plates from each other and forming V-shaped pockets or 30 troughs for receiving an adhesive liquid for retaining the dust. 20
12. An air filter, the dust-space of which is separated from the pure air-space by an endless chain, each chain link being composed of laminary plates strung up in parallel relation to the flowing direction of the air to be treated and provided with projections crossing the air direction, the height 35 of such projections corresponding to the distance of the laminary plates from each other and forming V-shaped pockets or 40 troughs for receiving an adhesive liquid for retaining the dust, the V-shaped pockets of one plate being reversed with respect to 45 those of the adjacent one. 35
13. An air filter, the dust space of which is separated from the pure air space by an endless chain, each chain link being composed of laminary plates presented edge- wise to the air flow, and having baffle portions extending along the plate and at an angle to the entering edge thereof and a container for oil located to serve as a bath through which the chain travels. 50
14. An air filter, the dust space of which is separated from the pure air space by an endless chain, each chain link being composed of multiple laminary plates strung up in parallel relation, and provided with projections extending into the interspaces, 55 said projections extending along the plates at an angle to the direction of air flow, a number of the projections of each plate being of sufficient height to contact with the opposed face of the adjacent plate, and a 60 container for oil located to serve as a bath through which the chain travels. 65
15. An air filter, the dust space of which is separated from the pure air space by an endless chain, each chain link being composed of laminary plates strung up in parallel relation to the flowing direction of the air to be treated, the opposed faces of adjacent plates being provided, respectively, 70 with ribs and recesses arranged at an angle to each other and crossing the air direction, and a container for oil located to serve as a bath through which the chain travels. 75
16. A sheet metal air filter having 80 V-shaped baffles struck up from the main body of the sheet metal in the path of the air to be filtered, and means to supply liquid to the surface of the sheet metal to render it adhesively retentive for dust particles and also to wash off the dust as it settles on 85 said sheet metal. 90
17. An endless self cleaning air filter disposed across the air passageway, said filter having tortuous flues for the air, said flues being formed to provide pockets adapted to hold liquid on the upwardly moving part of the belt and to discharge the liquid when on the downwardly moving side, and a container for liquid wherein the lower part of the belt dips in operation. 95

In testimony whereof, I affix my signature.

FRIEDRICH AUS DER MARK.
